DESIGN FOR A TOY MODEL SHIP'S HULL

William Kramer, Richmond Hill, N. Y.

Application January 10, 1935, Serial No. 54,784

Term of patent 14 years

To all whom it may concern:

Be it known that I, William Kramer, a citizen of the United States, residing at Richmond Hill, in the county of Queens and State of New York, have invented a new, original, and ornamental Design for a Toy Model Ship's Hull, of which the following is a specification, reference being had to the accompanying drawing, forming part thereof.

Figure 1 is a top plan view of a toy model ship's hull, showing my new design, and
Fig. 2 is a side elevation thereof.
Fig. 3 is a bow end view, and
Fig. 4 is a stern end view.

I claim:

The ornamental design for a toy model ship's hull, as shown.

WM. KRAMER.
